No. 721,687.

PATENTED MAR. 3, 1903.

J. FIRSCHING.

NETHER GARMENT.

APPLICATION FILED MAY 31, 1902.

NO MODEL.

UNITED STATES PATENT OFFICE.

JOSEPH FIRSCHING, OF UTICA, N. Y.

NETHER GARMENT.

SPECIFICATION forming part of Letters Patent No. 721,687, dated March 3, 1903.

Application filed May 31, 1902. Serial No. 109,585. (No model.)

To all whom it may concern:

Be it known that I, JOSEPH FIRSCHING, of Utica, in the county of Oneida and State of New York, have invented certain new and useful Improvements in Nether Garments; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

The object of my invention is to provide an undergarment for women's wear which is advantageously made in the main out of tubular fabric without material loss or waste and which garment will hang or set properly and well on the person.

In the drawings, Figure 1 shows a plan view of a section of tubular fabric cut according to my plan in order to construct the garment therefrom. Fig. 2 shows a rear view of the completed garment. Fig. 3 shows a gore-piece employed in the construction, two pieces like this being employed. Figs. 4 and 5 show flaps also employed in the completed garment.

Referring to the reference letters and figures in a more particular description, the upper fold of the tubular fabric shown is provided with the straight central slit or cut 1 2, the end at 2 of this cut entering a transverse slit or cut 3 4. The lower fold of the tubular fabric is provided with a shorter central longitudinal cut 5 6. The parts of the upper fold on either side are provided with the irregular cuts 7 8 9. These cuts described divide the rear fold into what may be termed the "body" portion A, the "extension" portions B B, and the remaining "strip" portions C C, while the lower fold at the outer end forms the forward portion D of the leg. The extension portions B B are turned outwardly, as indicated by dotted lines in Fig. 1, and the gore-pieces E are inserted and sewed along the outer edges to the edge of the extension portions B and along their inner edges to the outer edge of the parts C. At the lower end of the garment the inner

edges of the parts C are sewed to the inner edges of the part D, forming the legs of the garment, and the flaps F G are sewed, respectively, to the inner edges of the upper end of the part C, so that these flaps overlap 55 or overlie each other, and the upper ends of the flaps F G are inserted in the cut 3 and 4 and sewed in.

The garment may be provided with trimming and straps in any style desired. 60

What I claim as new, and desire to secure by Letters Patent, is—

1. A garment formed from tubular fabric having an enlarged hip and leg portion formed by making from similarly-positioned points 65 near either side of the rear fold, downwardly-converging cuts continued longitudinally to the end, gores inserted and secured in said cuts forming in part the rear of the leg, and the front fold of the tubular fabric being also 70 cut longitudinally at the legs and secured to the back forming the legs, substantially as set forth.

2. A nether garment formed from tubular fabric having an enlarged hip and leg portion 75 formed by cutting the rear fold from similarly-positioned points near each side of the fold on downwardly-converging lines and thence longitudinally to the end, and gores inserted and secured in said cuts, middle longitudinal slits in both folds of the tubular fabric, the edges of which are brought together and secured, forming the respective legs, substantially as set forth.

3. A nether garment formed of tubular fabric having an enlarged hip and leg portion formed by cutting the rear fold from similarly-positioned points near each side of the fold on downwardly-converging lines and thence longitudinally downward to the lower 90 end, and gores inserted and secured in said cuts, substantially as set forth.

4. A nether garment formed from tubular fabric having an enlarged hip and leg portion formed by inserting gores in cuts extending 95 from similarly-positioned points at each side of the rear fold in the rear fold on downwardly-converging lines extending thence longitudinally to the lower end of the fold, legs formed by securing together the edges of 100

middle longitudinal cuts in both folds of the lower end of the fabric, and overlapping flaps secured on the edges of the upper continuation of the middle cut in the rear fold, and at 5 their upper ends secured in a cut extending transversely, substantially as set forth.

In witness whereof I have affixed my signa-

ture, in presence of two witnesses, this 27th day of May, 1902.

JOSEPH FIRSCHING.
